CLOSURE CONSTRUCTION FOR
COLLAPSIBLE TUBES

Horace S. Hoggatt, Richmond, Ind.

Application September 2, 1939, Serial No. 293,272

8 Claims. (Cl. 221—60)

This invention relates to improvements in closure constructions for collapsible tubes.

The primary object of this invention is the provision of a closure construction for collapsible tubes such as are adapted to receive toothpaste, shaving cream, and the like, which is preferably an integral and permanent part of the tube, and adapted to normally assume a closed position, but which upon pressure will open the tube to permit of ejection of a quantity of the contents of the tube.

A further object of this invention is the provision of an improved closure construction for tubes, preferably collapsible tubes, which may or may not be of an integral construction with the tube, but which is relatively simple in nature, and of a practical construction, having no detachable parts which may become displaced or lost, and which may with facility be operated to dispense a quantity of the contents of the tube.

A further object of this invention is the provision of an improved closure construction for collapsible tubes which does not include any detachable cap parts, and preferably includes parts which may be a permanent part of the tube, operable in one hand of an operator to permit of instant ejection of a quantity of the contents of the tube, and which is of such nature as to automatically close the tube upon the release of hand pressure upon the part of the operator.

A further object of this invention is the provision of an improved collapsible tube for receiving paste materials which embodies an integral closure construction, and which may be manufactured at relatively low cost, and operated with facility to eject a desired quantity of the contents of the tube; the improved tube having a stream-line appearance and having no detachable parts.

A further object of this invention is the provision of an improved collapsible tube which embodies a closure construction which may be operated with facility by a person to eject a quantity of the contents of the tube, and which closure construction is of such a nature as to automatically close the opening upon release of hand pressure upon the part of the operator, and which through such action will tend to draw any residual part of the contents of the tube, which may be around the opening, into the tube, and thus prevent collection of contents of the tube at the dispensing aperture.

Other objects and advantages of this invention will be apparent from the following detailed description, taken in connection with the ac-

companying drawing, forming a part of this specification and wherein similar reference characters designate corresponding parts throughout the several views:

Figure 1 is a side elevation of the improved tube.

Figure 2 is a fragmentary cross-sectional view at the closure end of the tube, showing the tube closed.

Figure 3 is a view similar to Figure 2, but with the closure construction held in open position between the fingers of an operator.

Figure 4 is a cross sectional view taken substantially on the line 4—4 of Figure 2.

Figure 5 is a top plan view of the closure end of the tube, showing the dispensing opening closed.

Figure 6 is a perspective view showing the closure features of the improved tube.

In the drawing, wherein for the purpose of illustration is shown only a preferred embodiment of the invention, the letter A may generally designate the improved tube which embodies an improved closure construction B.

The tube A may be of any collapsible material, such as ordinarily is used for the reception of toothpaste, shaving cream, and the like; the improved tube not being limited to the dispensing of such substances. The tube A is preferably collapsible at its normally closed end 20, and at the opposite end the tube is stream-lined and provided with a closure construction B, over which the material of the tube is preferably fused or secured so as to hide the parts of the closure construction B, as are shown in Figure 6 of the drawing.

The closure construction B preferably consists of two pliant spring steel strips 25 and 26. The outer strip 25 includes the downwardly divergent leg portions 27 and 28 which are formed without apertures therein, and preferably which are of rather tapering width; tapering diminishingly upward to the arcuate or bight portion 29 which joins said legs. This bight portion 29 is preferably provided with a rectangular shaped dispensing opening 30 therein. The material of this spring steel piece 25 is of such nature that the legs 27 and 28 normally tend to assume their downwardly divergent position notwithstanding parts of the tube to which this strip may be affixed, nor the contents of the tube.

The inner steel spring strip 26 is secured within the strip 25. It includes a long leg portion 35 and a shorter leg portion 36. The portion 35 may preferably be a plane, and at its extreme

end, it is secured at 37, as by welding or soldering, to the inside at the lower end of the leg 28 of the strip 25, as is shown in Figures 2 and 6 of the drawing. Therefrom the leg 35 extends 5 at an acute angle upwardly and the arcuate or bight portion 41 to which the other leg 36 is connected is adapted to fit at the inside surface of the arcuate bight portion 29 of the steel piece 25, as is shown in the drawing. The leg 36, while 10 referred to as such, is preferably arcuated and adapted to move freely at the inside surface of the strip 25 along the inner surface of the leg 28 and the under-surface of the arcuate bight portion 26. Of course the steel spring piece 26 15 normally tends to unfold, and thus it is maintained in close frictional engagement with the inside surface of the strip 25, in the relation shown in the drawing. The leg portion 35 of the strip 26, inasmuch as it crosses the outlet 20 20 of the tube, is provided with an opening 40 through which the material of the tube may readily flow, although this opening 40 is not the dispensing opening. The arcuate or bight portion 41 of the strip 26 has a dispensing opening 25 25 43 therein which is normally out of alignment with the dispensing opening 30 of the strip 25 when the strips 25 and 26 are expanded, as is shown in Figures 2 and 6 of the drawing. This is their normal position, according to the inherent 30 springiness of these strips. The opening 43 may, however, be moved to align with the dispensing opening 30 merely by pressure at the free ends of the leg portions 27 and 28 of the strip 25. This 35 action will force the arcuate bight end 40 of the strip or piece 26 and the leg portion 36 thereof along the inside surfaces of the bight portion 29 and leg 28 of the piece 25, to align the openings and permit dispensing of the contents of the tube, as is shown in Figure 3 of the drawing. 40 The end portions of the strip 26 may be less in width than the legs of the strip 25, inasmuch as the latter is intended to maintain the proper shape and positioning of the collapsible end of the tube. 45 The pliant material of the tube proper may be fused or secured along the outer surfaces of the legs and bight portion of the closure strip 25, as is shown in the drawing. Of course the collapsible material of this tube will flex, along 50 50 with the leg portions of the closure strip, as is quite evident from an inspection of Figures 2 and 3 of the drawing.

It is preferred to streamline the closure end of the tube, as shown in Figure 1 of the drawing, and this is one reason for tapering the width of the closure strips or pieces. 55

It is apparent from the foregoing that the collapsible tube closure construction will enable a facile operation of the tube; permitting ejection of a desired amount of the contents of the tube merely by pressure of the leg portions 27 and 28 of the closure construction end of the tube together. This action aligns the dispensing openings of the strips 25 and 26, and compels 60 60 the dispensing of the contents of the tube inasmuch as pressure of the fingers of the operator will restrict the capacity of the tube at the dispensing end thereof.

It is obvious that there are no detachable cap parts of the tube. The closure action of the portions 25 and 26 of the closure construction is automatic, and this action, tending as it does to expand the end of the tube, will withdraw any residue portions of the contents of the tube 65 65 into the tube from the dispensing opening, as the

latter is being closed; thus preventing the gathering of the contents of the tube around the dispensing opening and maintaining the tube in a sanitary and neat appearing condition.

It is preferred to provide rectangular openings at the dispensing end of the tube, although it is realized that other shaped openings may be provided, and the end of the tube may be shaped other than that shown in the drawing.

Various changes in the shape, size, and arrangement of parts may be made to the form of invention herein shown and described, without departing from the spirit of the invention or the scope of the claims.

I claim:

1. In a receptacle for receiving fluid materials the combination of a container portion, and a closure portion, said closure portion including yieldable spring parts each having dispensing openings therein, said spring parts inherently positioning themselves to maintain the dispensing openings out of alignment and being positioned so that upon pressure they may be distorted to move the openings into alignment for dispensing materials from the receptacle.

2. A closure arrangement for receptacles, such as collapsible tubes, comprising complementary slidible and flexible closure portions, one of which at least inherently assumes a definite relation with respect to the other, said parts having dispensing openings therein normally out of alignment when the said parts assume their normal position, and being in alignment when the said parts are flexed.

3. A closure construction for collapsible tubes and the like comprising a U-shaped piece of spring material having leg portions and a bight portion, the bight portion having a dispensing opening therein, said piece tending to assume a definite position from which it may be flexed, and a second part attached adjacent the outer end of one of the legs of the first mentioned piece and extending therefrom across the space between said legs and having an arcuate portion complementary to the bight portion of the first mentioned closure piece and having also a dispensing opening therein adapted to align with the opening of the first mentioned piece only when the legs of the first mentioned piece are brought together against the normal tendency of said first mentioned piece to maintain said legs in spread condition.

4. In a collapsible tube the combination of a collapsible tube body, and complementary spring actuated closure parts having dispensing openings therein, said closure parts being normally spring actuated to maintain said openings out of alignment and flexible under pressure to position said openings in alignment when the tube is squeezed at a designated location for dispensing materials therefrom.

5. In a fluid dispensing tube the combination of a tube body, complementary relatively movable closure parts having dispensing openings therein, said closure parts both being spring actuated to normally assume a relative position with the dispensing openings out of alignment, the closure parts being so related to the tube that they may be relatively moved to place said openings in alignment for dispensing the contents from the tube, the spring actuation of said parts automatically tending to place said dispensing openings out of alignment upon release of pressure.

6. In a collapsible tube the combination of a collapsible tube body, and a closure construction

connected to the collapsible tube body comprising a pair of complementary related resilient parts each having openings therein, said parts being relatively connected and having portions thereof provided with dispensing openings therein which are relatively slidable so as to align the openings when pressure is applied so as to distort said closure portions against their inherent resilient tendency.

7. A closure construction for collapsible tubes and the like comprising a substantially U-shaped strip of spring material including leg portions and a bight portion, the bight portion having a dispensing opening therein, and a second strip of springy material having a part secured adjacent the outer end of one of the legs of the first mentioned strip and extending therefrom diagonally across the space between the legs of the first mentioned strip and having a bight portion adapted to slidably fit at the inner side of the bight portion of the first mentioned strip, the bight portion of the second mentioned strip also having a dispensing opening therein out of alignment with the dispensing opening of the bight of the first mentioned strip when the first mentioned strip is in normal position, relative movement of the legs of the first mentioned strip towards each other being adapted to move the

bight portion of the second mentioned strip to align the openings of both of said bights.

8. A closure construction for collapsible tubes and the like comprising a substantially U-shaped strip of spring material including leg portions and a bight portion, the bight portion having a dispensing opening therein, and a second strip of springy material having a part secured adjacent the outer end of one of the legs of the first mentioned strip and extending therefrom diagonally across the space between the legs of the first mentioned strip and having a bight portion adapted to slidably fit at the inner side of the bight portion of the first mentioned strip, the bight portion of the second mentioned strip also having a dispensing opening therein out of alignment with the dispensing opening of the bight of the first mentioned strip when the first mentioned strip is in normal position, relative movement of the legs of the first mentioned strip towards each other being adapted to move the bight portion of the second mentioned strip to align the openings of both of said bights, the leg of the second mentioned strip having an opening therethrough to permit free flow of material to be dispensed at all times.
